Primary Examiner — Mary Ann Calabrese*Assistant Examiner* — Megan M Majcher Hartnett(57) **CLAIM**

The ornamental design for a display screen or a portion thereof with a graphical user interface, as shown and described.

DESCRIPTION

The sole FIGURE is a front view of a display screen or a portion thereof with a graphical user interface showing a new design.

The broken lines form no part of the claimed design. The outer edge of the portion of the display screen is understood to be congruent with the outer edge of the graphical user interface.
